UNITED STATES PATENT OFFICE.

THOMAS N. MORSE, OF FAIRHAVEN, MASSACHUSETTS.

IMPROVEMENT IN METHODS OF WARMING RAILROAD-CARS.

Specification forming part of Letters Patent No. 96,945, dated November 16, 1869.

To all whom it may concern:

Be it known that I, THOMAS N. MORSE, of Fairhaven, in the county of Bristol and State of Massachusetts, have invented a new and Improved Method of Warming Railroad-Cars; and I do hereby declare that the following is a full, clear, and exact description thereof, reference being had to the accompanying drawings, making part of this specification, in which—

Figure 1 is a sectional view of portions of the frame-work of two cars having my improvements applied to them. Fig. 2 is a plan view of the heating apparatus and the joints of the ends of the hot-air pipes. Fig. 3 is a diametrical section through one of the registers. Fig. 4 is a diametrical section through the steam-boiler and its air-heating pipes.

Similar letters of reference indicate corresponding parts in the several figures.

The main object of this invention is to warm railroad-cars by means of air which is heated in its passage through pipes arranged in a steam-boiler, and which is thence conducted through pipes and registers into the cars. Another object is to connect the ends of the pipe of one car with the ends of the pipes of other cars by means of telescopic joints combined with double ball-and-socket joints, which will accommodate themselves to all the motions of a train, allow a coupling or uncoupling to be readily effected, and automatically close the ends of the pipes when cars are disconnected.

I am aware that prior to my invention attempts have been made to warm railroad-cars by means of air which was heated by conducting it through pipes arranged in a furnace-chamber, and then introducing the air thus heated into cars by means of pipes and registers. Air when heated in this way is dry and unpleasant.

I am also aware that steam has been used for warming cars; but owing to the difficulties attending the carrying of steam under pressure from one car into another, and its rapid condensation in the pipes, this method is very objectionable.

I am also aware that ball-and-socket joints have been used with sliding joints for making the connections between the ends of pipes; but I am not aware that pipes have ever been con-

nected in the manner and for the purposes hereinafter set forth.

The following description of my improved method of warming cars will enable others skilled in the art to understand how to carry it into effect.

In the accompanying drawings, A is intended to represent a portion of a baggage or other car which is in front of the passenger-car A'.

B is a steam-boiler of suitable capacity, which is arranged in a convenient position in the car A, and constructed with a fire-chamber, b, and vertical flues d d.

a is the door leading to the fire-chamber. c is the ash-pit; and B' is the smoke-pipe, which may lead out through the roof of the car A.

Within the water-chamber of the boiler B is a pipe, g, which may be coiled around the flues d, so as to obtain in a very compact space a considerable length of pipe.

If desirable, the pipe g may be carried through the fire-chamber from a spout, g', so that the air will pass through the fire-chamber, and thence through the water-chamber on its way from an air-forcing engine, C, to a branch pipe, g'.

The steam-boiler shell should be made strong, to resist considerable pressure of steam, and it should be furnished with a safety-gage valve, a', and with cocks and other appendages belonging to boilers for driving-engines.

The pipe or spout g' communicates at one end with the lower end of the air-pipe g and at the other end with a rotary fan-case, C. Within this case C a fan is arranged, carrying on its shaft a pulley, e, around which a belt, f, passes, which is also passed around a wheel on one of the car-axles. In this way the rotary motion of the car-axle can be made to drive the fan. If it is desired to give motion to the fan or any other suitable pneumatic engine when a train is at rest as well as when it is in motion, I shall employ a small engine and drive it by steam taken from the boiler B. When steam is made in the boiler B and the fan in case C is rotated air will be forced into and through the coil of pipe g and heated by the hot water and steam in the boiler B. The air thus heated is conducted through the vertical pipe g' and delivered into a pipe, D, which is arranged beneath and permanently attached

to the bed of the car A. The forward end of pipe D should be closed to prevent the escape of air from it in this direction. Pipe D may be inclosed in any suitable substance which is a poor conductor of heat, and this pipe or conduit may be made cylindrical or flat in cross-section. From the pipe D beneath the car A the air is conducted into the pipe D beneath the passenger-car A' and received into this car in suitable quantities through registers E, which are located at suitable points along the bottom or floor of this car A.

The following is a description of my mode of connecting together the ends of the two pipes of cars A and A': The end of the pipe D of car A is made flaring and ground out so as to form a socket, i, adapted to receive a ball, j. This ball is hollow, and has a hole at o and a tube at k, which latter is diametrically opposite the hole o, as shown in Fig. 1. On opposite sides of the ball j are pins, to which springs h h are secured, which springs are attached to the pipe D of car A by hooks, as shown in Fig. 2. It will be seen that springs h h will hold the ball j snugly into its socket and allow a free universal articulation of this ball. When the tube k is in the position indicated in Figs. 1 and 2 air will freely escape from pipe D through it; but if the free end of this tube k is allowed to drop and assume a position at right angles to its pipe D the solid portion of ball j will shut the end of this pipe and prevent air escaping therefrom. In this way the ball j is made to automatically close the end of its pipe D when car A is disconnected from car A'. The pipe D which is beneath car A' has its ends provided with articulating tubular connections constructed precisely like the connection on pipe D of the car A. The short tube k' is made large enough to receive into it the tube k, as shown in Figs. 1 and 2, and to allow a free endwise motion.

When the two pipes D D are connected by the double ball-and-socket joints and sleeve-joint, as above described, there will be a free passage for air through the jointed parts, and these parts will articulate freely and accommodate themselves to all the motions of the car.

In practice the pipes D D will terminate on one side of the center of the width of the cars, so as to be out of the way of buffers and couplings, which may be of the well-known or improved kind.

In Figs. 2 and 3 I have shown the construction of one of the registers for distributing the heated air into the cars from the pipes or conduits D. E represents a vertical cylinder with closed bottom and open top, which is in communication with pipe D at p', and which is permanently applied to the floor of the car. Within this cylinder is a tube, n', which is open at its bottom and provided with a perforated top, n. A portion of the tube n' is removed at p, so that when this opening is brought opposite the opening p' a commun-

cation is established between the register-chamber and warm-air pipe D. By turning the tube n' more or less a greater or less quantity of air can be admitted into car, or the influx of air can be shut off altogether.

I have previously stated that when two cars are disconnected the free ends of the tubes k k' will drop down, so that these tubes will assume positions at right angles to their respective pipes D.

In making up a train the cars are coupled together in the usual manner, after which the tubes and balls are dislocated from their respective sockets, which will be allowed by the springs h h'. The said tubes are then connected by slipping one into the other, and their balls returned into their sockets.

By the invention which I have above described I am enabled to practically warm railroad-cars by properly-tempered air which is heated by conducting it through a pipe arranged inside of a steam-boiler, and thence forcing it through pipes arranged beneath the car-beds and connected together at the ends of the cars by means of ball-and-socket and sleeve couplings. Instead of using the boiler for heating air to be forced into the cars in the summer season, ice might be put into the chamber which was used for the water, which would refrigerate the air forced through the coil of pipe, and in this way fruits and vegetables could be preserved for a considerable length of time during transportation in cars.

I am aware that it is not new to form a coupling between the ends of pipes arranged beneath railroad cars by the combination of a telescopic joint and two ball-and-socket joints when the latter are permanently attached to the said pipes; and such combination I do not claim as my invention. I have combined with two ball-and-socket joints and a telescopic joint a third element—to wit, springs for holding the ball-and-socket joints together and allowing of their dislocation when desired to effect a coupling, as hereinabove explained.

Having described my invention, what I claim as new, and desire to secure by Letters Patent, is—

1. An air-forcing apparatus, in combination with a pipe leading through the steam and water space of a steam-boiler, and communicating with pipes which are arranged beneath the car-beds, and which are connected by hollow universal joints, substantially as described.

2. The construction of the flue-boiler B, with an air-pipe arranged within its water and steam space, substantially as and for the purposes described.

3. The combination of balls and sockets i j i' j', telescopic joint k k', springs h h', and pipes D D, constructed and put together substantially as described.
